[57] CLAIM

The ornamental design for an ice cream cone confection, as shown and described.

DESCRIPTION

FIG. 1 is a perspective view of an ice cream cone confection showing my new design;

FIG. 2 is a right side elevational view thereof;

FIG. 3 is a left side elevational view thereof;

FIG. 4 is a top plan view thereof;

FIG. 5 is a bottom plan view thereof; and,

FIG. 6 is an end view with the opposite end being a mirror image.

The contrasting shading inside the cone represents simulated ice cream.
